LEONARD CHARLES BARKER, OF EDGEWATER, NEW JERSEY.

MECHANICAL TOY BASEBALL.

Application filed October 5, 1926. Serial No. 139,699.

My invention relates to games or toys and refers more particularly to a miniature base ball game for indoor use wherein the playing field is proportionately in size to that of a regulation field.

One object of my invention is to provide a toy base ball game that will contain all the essential features of the game as it is played upon a regulation field.

10 Another object of my invention is to provide means whereby the batter may manipulate the spring operated bat at will, in a way that is similar to that of a batter in a regulation game.

15 A further object of my invention lies in the operation of the pitching mechanism which will allow the pitcher to control the speed of the ball mechanically.

20 A still further object of my invention is to provide a miniature game board whose operation is dependent upon the skill of the two operators, each of which represents the opposing teams.

25 With these and other objects in view, my invention resides in the features of construction, arrangement of parts, and method of operation which will hereinafter be fully disclosed in the specification and illustrated in the drawings, wherein like reference characters refer to similar parts throughout the several views.

Figure 1 is a plan view of the device.

Figure 2 is a section on line 2—2 of Figure 1.

35 Figure 3 is a section on line 3—3 of Figure 1.

Figure 4 is a section on line 4—4 of Figure 1.

Figure 5 is a plan of one of the markers.

40 Figure 6 is an elevation of one of the markers.

Figure 7 is an isometric view of one of the clip markers that are used in recording the strikes and outs.

45 The playing field of this device is, of course, of greatly reduced area but is proportionate to a regulation base ball field.

This board, for the sake of illustration, is shown as made up of a field 1, being held by

and within a frame or moulding 2, with curved corners 3.

The field 1, is held approximately in the central part of this frame 2, by the shoulder 4, against which the same fits or is held by any suitable means.

55

The lower part of this frame 2, has a shoulder 5, into which fits and is held by any suitable means, a bottom 6.

This board thus forms a box like structure with the field 1, wholly surrounded by a wall within which the ball 7, may be manipulated as will be hereinafter more fully described.

60 In playing the game it is necessary that the field 1, should be levelled and to take care of that there is provided, on the under side of each corner, a downwardly projecting screw fastened thereto as shown in Figure 1 by 8, said screw having a ball nut 9, thereon, so that the board may be leveled by adjusting these four ball nuts and by the aid of the levels 9^a and 9^b, as shown in Figure 1.

65

70 The field 1, is marked off into a diamond as shown by the lines 10 and 11, between which are the base lines 12, the pitcher's box 75 13, and the home plate 14.

Near the home plate 14, are the pits 15 and 16, for the sides in the field and at the bat respectively, these pits bounded by the lines 17 and 18 and the wall of the field 1.

80

There are nine holes 19, in each of these pits which fit the players 20, one of which is shown in Figures 5 and 6, each player having a pin 21, on the bottom which fits into these holes 19.

85

When the side in pit 15, has the field, the players are placed in the field in their proper positions.

The catcher represented by IKE—C is placed in hole 22, the pitcher HAL—P in 90 hole 23, the first base BUD—1B in hole 24, the second base GAR—2B in hole 25, the third base DEL—3B in hole 26, short stop FAT—SS in hole 27, right field ABE—RF in hole 28, left field ELY—LF in hole 29, center field CAL—CF in hole 30 and the 95 umpires not shown in the holes 31 and 32.

The side at the bat are moved, as the play

- progresses, from hole to hole that is to say from hole 33, at first base to hole 34 at second base, to hole 35, at third base and when a home run is made to the pit from whence 5 the runner came.
- There is a foul line fence 36, at first base and near that point is an oval hole 37, which will hold the ball 7, and when the ball lands in this hole the batter will be out.
- 10 Near the third base is another foul fence 38, and a hole 39, which serves for the same purpose as does hole 37.
- There are oval holes in the field, 40 in front of the catcher's position 22, 41 in front 15 of the first base 24, 42 in front of the second base 25, 43 in front of the third base 26, 44 in front of the short stop 27, 45 in front of the right field 28, 47 in front of the left field 29, and 46 in front of the center field 30.
- 20 Above and partly encircling these holes is a frame work 48, having a beveled edge 49, supported by washer or washers 50, and held by screws 51 and nuts 52, as shown in Fig. 4.
- 25 This bevel is provided so that when a ball is batted within the reach of this frame, the beveled edge will tend to direct the ball into the oval hole provided for that purpose and the batter is out.
- 30 This same principle applies to all of the holes 40, 41, 42, 43, 44, 45, 46 and 47 and when the ball clears all of the holes and lands into any of the holes 53, 54, 55 and 56, it means that the batter has a three base hit 35 but if it lands behind the lines 57 and 58, and not in the holes 53, 54, 55 or 56, it means a two base hit.
- The rectangles 59 and 60 are representative places for the rooters and like the spaces 40 12 and 13 are preferably painted white while the main field is green.
- 45 The space between the first base frame work and the foul fence through which a batted ball can travel is one and one quarter ball diameters, between the first and second base is two ball diameters, and between the second base and short stop is three ball diameters, between short stop and third base is two ball diameters or one and one half ball 50 diameters between the pitcher and second base and pitcher and short stop, between the third base and the foul line is one and one quarter ball diameters, between the right field and the wall is one ball diameter. The 55 spacing, not batting spacing, between the right field and the center field is ten ball diameters, between the center field and the left field is ten ball diameters and between the left field and wall is one ball diameter, so 60 that it can be readily seen that it is not very easy to get a two base or three base hit or home run in this game.
- The ball is pitched by a tension spring 61, which is connected on one end to an ear 62, on a sliding piece 63, which slides between 65 two guides 64 and 65, held positioned by the rivets 66, and the other end of this slide has an extension or ear 67, which extends up through a slot 68, in the field 1.
- The other end of this spring 61, is connected 70 to a wire 69 or other operating means, passes over the rotatable wheel or spool 70, to a ring 71, through a hole 72 in the frame 2.
- This ball propelling slide 63, when pushed by hand back away from the pitcher is held 75 under tension of the spring 61, by the latch 73, which is provided with a sloping head 74, a spring 75, a stem 76, a stop head 77, a body 78, holding rivets 79 and a guide pin 80.
- To the end of the stop head 77, a rod or 80 wire 81, is attached which passes through the hole 83, in the frame 2 and engages a ring 82.
- Thus when the slide 63, is forced back by the player who has the field, the latch 73, will spring in front of the ear 67 and hold 85 the slide under an initial tension and upon the release of the latch 73, the ball 7, when placed in the slot 68, against the ear 67, of the slide 63, will be propelled toward the home plate but if there is an additional tension made upon the tension spring 61, by pulling the ring 71, operating the wire 69, passing over the roller or pulley 70, the ball 90 will move at a speed dependent upon what tension may be placed upon the spring 61, so that it is self evident many speeds of delivery of the ball may be obtained.
- The bat 84, a miniature of a regulation 95 bat, is fastened to a shaft 85, having a collar 86, and a shoulder 87, which holds the 100 same in position between the frame 1, and the bottom 6.
- This shaft 85, has a coil spring 88, one end of which 89, is firmly fastened to the shaft 85, and the other end 89a to the field 1. 105
- The collar 86, has a pin 90, which limits the movement of the shaft 85, carrying the bat 84, by engaging the stop pin 91.
- The bat, when operated, is moved by the 110 batter's hand in the direction of the arrow 92, until it has reached the dotted position 93, where it is held by the pin 94, on the arm 95, pivoted at 96, in the lug 97, and normally held out of engagement with the bat 84, by the spring 98.
- When the bat is moved around to the position 93, the batter presses down the end 99, of the lever 95, and when the pitcher pitches the ball 7, toward him, he lets go of the lever 115 at 99, and if his judgment is good, the bat 120 moving as shown by the dotted line 100, may bat the ball 7, as shown in Figure 1, by the dotted lines 101.
- The rubber obstructions or barriers 102 and 103, near the center field are provided 125 so that if the ball hits them it will go over the wall or fence for a home run.
- In the rules of play, in all infield outs, the

batter is out and any runners on base are advanced one base but not further than the third base.

In all outfield outs, the batter is out, and 5 the runners on base advance one base and a man on third base would score.

If a batted ball is returned by a fielder to foul territory, with no one on base, the batter is out, with one on base the runner is out 10 and the batter goes to first base, with more than one on bases, the fielder returns the batted ball to the right field foul territory, the last runner to get on base is out, the other runners advance one base and the batter 15 takes first base.

When a batted ball is returned to left field foul territory with more than one on base, the most advanced runner is out, the other runners advance one base and the batter 20 takes first base.

If the fielder returns a batted ball to a right field dugout with none on base, the batter is out, with one on base, it is scored as a double play, with more than one on 25 bases, it is scored as a double play, the batter and the last man to get on base are out and other runners advance one base.

If fielder return a batted ball to the left field dugout with two or more on base, it is 30 scored as a double play, the two most advanced runners are out, the batter takes first base and if there be another runner, the other runner advances one base.

If the fielder returns a batted ball to the 35 catcher's box, with two or more runners on bases, it is scored as a triple play, if there were none out, it retires the side, with one on base it scores as a double play and with none on bases the batter is out.

40 Balls batted fair that come to a stop on fair territory are scored as singles except those that stop in two or three base hit territory.

A ball driven between the first baseman 45 or between the third baseman and the foul line is scored as a two base hit and is not an out if the ball is caught by a fielder after the ball has been driven through one of these openings.

50 When the ball hits the back fence or wall, it scores as a two base hit and when the ball comes to a stop in one of the openings back of the centerfielder, it is a three base hit.

Home runs are when the ball hits one of 55 the rubber obstructions or barriers in front of the center field and hops over the fence or wall.

Fouls are out when the foul ball comes to 60 a stop in the holes on either side of the foul territory.

On each side of the field 1, attached to the fence or wall 2, are clip markers 104, one for marking the outs and the other for marking the strikes, which markers consist of a base

105, having two recesses 106 and 107, into 65 which fit two clips 108 and 109, as shown in Figure 7, 108 is down and 109 is up.

These clips 108 and 109 are pivoted by the pin 110, and held in position by the springs 111 and 112. 70

Having thus described and illustrated the preferred embodiment of my invention, I do not wish to limit myself to the exact construction shown as modifications may be made without departing from the spirit of 75 the invention or scope of the claims.

I claim:

1. In a base ball apparatus of the character described, the combination with a playing field surrounded by a wall or fence, of a 80 multiple of oval pockets in spaced relation with each other representative of players' positions and other pockets for fouls and three base hits, each of the said pockets representing players' positions having a 85 guiding beveled framework directing the ball into said pockets, mechanically operable means controlling the speed of and directing a ball to roll at speeds variable at will by the operator, towards the batter and spring 90 operable, manually set and releasable means for batting the rolling ball.

2. In a base ball apparatus of the character described, the combination with an enclosed field, of a multiple of oval shaped ball 95 receiving and retaining pockets, a multiple of ball deflecting resilient barriers, means by which the strength of the spring against which the pitcher is operated may be varied at the will of the operator, means guiding 100 and directing the ball toward the batter, mechanically operable manually releasable means for batting the rolling ball and means recording the outs and strikes.

3. In a base ball apparatus of the character described, the combination with a fenced playing field, of a multiple of oval ball receiving and retaining pockets, those which are in representative players' positions having means directing a ball therein, means 110 for utilizing markers representative of the players in proper positions, means for rolling a ball at various speeds toward the batter, means for batting the rolling ball and controlling the release of said bat and means 115 for recording the outs and strikes.

4. In a base ball apparatus of the character described, the combination with a fenced playing field, of a multiple of oval ball receiving and holding pockets in representative players' positions each provided with marker holding means, means for rolling a ball at various speeds toward the batter, means for batting the rolling ball, means for recording the outs and the strikes and means 120 for leveling the said apparatus.

5. In a base ball apparatus of the character described, the combination including a

playing field, a horizontally movable, miniature spring operated, pivoted bat, a marked diamond, foul line fences, a multiple of resilient barriers and oval ball receiving pockets, and means for pitching the ball at various speeds, by varying at the will of the operator, the strength of the spring against which the pitcher is operated and means releasing the said variable spring 10 operating means and guiding the ball toward the batter.

6. In a base ball apparatus of the character described, the combination with a play-

ing field, of a leveling means, a marked diamond and subdivided field, a pivoted, 15 miniature, spring operated bat, manually set and released, a multiple of barriers and ball receiving and holding pockets, means for rolling, guiding, manually controlling the speed of and releasing the ball propelling 20 means and means for recording the strikes and outs.

Signed at New York, in the county of New York and State of New York this 4th day of October, A. D. 1926.

LEONARD CHARLES BARKER.
